JOSEPH A. COYLE, OF AMSTERDAM, NEW YORK, ASSIGNOR TO BIGELOW-SANFORD CARPET CO., INC., OF THOMPSONVILLE, CONNECTICUT, A CORPORATION OF MASSACHUSETTS

AXMINSTER LOOM

Application filed July 31, 1931. Serial No. 554,173.

The present invention relates to Axminster looms and an object thereof is to provide a machine which will cause each tube frame to wipe-in a plurality of successive times, that is, to repeat one or more times the wiping-in operation before being carried away by the transporting carrier. Another object of the invention is to provide a novel means for rendering the feeding mechanism 10 of the transporting carrier inoperative during one or more wiping-in operations of each tube frame so that the wiping-in mechanism may operate on a single tube frame a plurality of times. A further object of the invention is to provide a novel means of supporting the shearing blade carriers at intermediate points for the purpose of preventing the sagging of such carriers. A still further object of the invention is to provide a wiper which will remove from the strands depending from the tube frames, loose yarn 20 to prevent the latter being incorporated in the completed fabric. In addition to the above the present invention provides for modifying the action of the cloth take-up during successive wiping-in operations by the same tube frame, that a plurality of rows of the same pattern or color may occupy substantially the same space longitudinally of the fabric that is ordinarily occupied by a single row of tufts to thereby produce a so-called "quality" fabric.

This application is a continuation in part of application Ser. No. 298,688, filed August 35 10, 1928.

To these and other ends, the invention consists of certain parts and combination of parts, all of which will be hereinafter described, the novel features being pointed out 40 in the appended claims.

In the drawings:—

Fig. 1 is a side view of a machine with parts removed to illustrate the operation of the selecting or limiting mechanism for the feeding mechanism of the transporting carrier;

Fig. 2 is a fragmentary vertical section showing a tube frame about to be returned to wiping-in position by the wiping-in mechanism after the feeding mechanism for the

transporting carrier has been rendered ineffective;

Fig. 3 is a view similar to Fig. 2 showing the tube frame immediately after a wiping-in operation and just prior to the shearing of the yarn by the shearing mechanism;

Fig. 4 is an enlarged detail view of the shearing mechanism showing the manner in which the shearing blades are supported intermediately of their ends;

Fig. 5 is a detail view showing the manner in which the selecting or limiting mechanism for the feeding mechanism of the transporting chain is rendered effective;

Fig. 6 is a fragmentary plan view of the comb;

Fig. 7 is a plan view of the shearing mechanism and wiper;

Fig. 8 is a side view illustrating the manner in which the shearing mechanism and the wiper are operated;

Fig. 9 is a side view showing more fully the take-up and means for modifying the take up during successive wiping-in operations of the same tube frame; and

Fig. 10 is a front view of the means for modifying the take-up operations.

Referring to the illustrated embodiment of the invention, 1 indicates the main frame of the loom having a drive shaft 2 supported thereon. Also supported on this main frame are two rolls 3 containing the warp threads which lead from the rolls over the two tension devices 4 to the breast plate 5 over which the completed fabric travels. The main frame has a portion 6 with a forward projecting arm 7 provided with a bearing 8 in which the drive shaft 9 of the transporting carrier or chain 10 turns. A sprocket 11 is arranged on the drive shaft 9 and engages the transporting chain 10. This chain is of the usual construction and carries the yarn spools 12 and tube frames 13 which may be of any suitable construction. Operation of the transporting chain or carrier 10 is effected, in this instance, by a ratchet wheel 14 arranged on the drive shaft 9 and adapted to be engaged by two pawls 15 and 16 pivoted respectively on two swinging arms 17 and 18 mounted to turn on the drive shaft 9. To

these swinging arms 17 and 18 are pivoted at 19 two links 20 which have a common pivot 21 on the double arm lever 22 pivoted at 23 on an arm 24 supported on the upright 5 6 of the frame, Fig. 3. To the other end of this lever 22 a link 25 is pivoted, this link 25 in turn being pivoted at 26 to a lever 27, Fig. 1, and the latter being pivoted at 28 to the frame of the machine and carrying the 10 roller 29 for cooperation with the cam 30 on the drive shaft 2. It is apparent that, with the turning of the drive shaft 2, the lever 22 will be rocked on its pivots 23 and will move the pawls 15 and 16 upwardly simultaneously, the pawl 15 acting on one of the teeth of the ratchet wheel 14 and shifting the transporting carrier 10. At the same time, the 15 pawl 16 engages behind one of the teeth on the ratchet wheel 14 so that upon the descent 20 of the lever 22 the pawl 16 will complete the movement of the transporting carrier 10 and bring another one of the tube frames with its yarn spool to a position where it may be operated upon by the wiping-in mechanism.

The operation of wiping-in the yarn from the different spools is effected by a well-known mechanism comprising, in this instance, rocking carrier 31 pivoted at 32 and 30 rocked by means of links 33 which are operated from the drive shaft 2. Each of these rocking frames 31 of which there are two, one at opposite sides of the loom, carries a lever 34 pivoted at 35 between its ends on the carrier and having an end portion 36, Fig. 2, which is adapted to interlock with one end of a tube frame 13 to pivotally support the tube frame while the latter is detached from the transporting carrier 10. Mechanism not 35 shown and old in the art is provided for swinging the two arms 34 on the pivots 35 in order to impart to the tube frame and its spool a longitudinal movement. For imparting a rocking movement of a tube frame 40 and its spool on the arms 34, two links 37, Fig. 2, are provided each detachably interlocking at one end with a tube frame 13 above the pivotal connection with the arms 34, each of said links being pivotally connected at 38 to an arm 39 pivoted at 40 to the frame extension 6 and operated by a link 41 from the shaft 2. The details of this wiping-in mechanism are not shown, as the mechanism is well-known and is not changed in 45 the present invention.

After each pattern line is wiped-in by a tube frame, a shearing mechanism cuts the tufts from the yarn on the tube frame. The shearing mechanism comprises, in this instance, a rear blade carrier 42, Figs. 2 and 4, provided with a cutting blade 43 and a front blade carrier 44 provided with a cutting blade 45. These blades are guided at 50 their ends on side pieces of the main frame 1 at 88 and 89. To each end of the blade car-

rier 44 are pivoted links 90, Fig. 8, each of which is pivoted at 91 to the upper end of one of two levers 92, the lower ends of which are pivoted at 93 to the frame 1. Each lever 92 carries a roller 94 which cooperates with the cam 95 on the drive shaft 2. To the opposite ends of the knife carrier 42 are pivoted links 96, Fig. 8, which in turn are pivotally connected to the upper ends of double arm levers 97. The lower ends of these levers are in turn pivotally connected to links 98 which pivotally connect with the upper ends of levers 99 pivoted at 100 on the frame and having rollers 101 engaged by cams 102 on the shaft 2. It will thus be seen that the two knife carriers are moved in opposite directions from the shaft 2 first toward each other and then away from each other.

As the shearing blade carriers are only supported at their ends and in a wide rug they have considerable length, there is a tendency for the carriers to sag at their middle portions and to prevent this sagging is one of the features of this invention. This means comprises intermediate supports for both knife carriers 44 and 42 between the ends of the carriers. The knife carrier 42 has an adjustable bracket arm 46 bolted at 47 to the rear sides of the carrier 42 and projected upwardly and rearwardly from the carrier at an intermediate portion thereof. On the frame portion 6 an arm 48 is secured by bolts 49 and projects forwardly and downwardly from the frame, its lower end being provided with an adjustable guide member 50 which is pivoted to the arm 48 at 51 and is held in its adjusted position by a bolt 52, passing through the slot 53 in the guide member. An adjustable abutment 54 on the arm prevents the shifting of the guide member 50 in an upward direction. A pin 55 on the adjustable arm 46 travels in the guide groove of the guide member 50 as the knife carrier 42 moves back and forth.

The intermediate support for the knife carrier 44, Fig. 4, embodies an arm 56 projected forwardly and upwardly from the knife carrier 44 and carrying a grooved guide member 57 which is adjustably mounted on the arm 56 preferably by a means of two bolts 58 operating in slots 59 in the guide member 57 and anchored in the arm 56. Adjustable abutments 60 cooperate with the guide member 57 to hold it in its adjusted position.

On the guide member operates a roller 61 projected laterally from an adjustable bracket 62 depending from the underside of a cross piece 63 which extends across the front of the loom and is supported from the frame 1 by an upright extension 64, Fig. 7, on the side pieces of the main frame of the loom.

Another feature of this invention is the provision of means whereby the wiping-in operation of each tube frame may be repeated,

that is, may be made to give two or more wiping-in operations successively before another tube frame is wiped-in. This means, in this instance, renders the feeding mechanism of 5 the transporting carrier 10 inoperative while the successive wiping-in operations of the tube frame are taking place so that when the wiping-in mechanism returns the tube frame and its spool to the transporting carrier it 10 is compelled again to take up the same tube frame and spool and carry it again to the fabric being woven or to wiping-in position. This result is accomplished, in this instance, by limiting the swinging movement of the 15 operating lever 22 so that the pawls 15 and 16 move back and forth over the ratchet wheel 14 without imparting any movement to such ratchet wheel and consequently not imparting any movement to the transporting 20 chain 10. The limiting means, in this instance, comprises an endless member or chain 65, Figs. 2 and 3, mounted to travel on two sprockets 66 and 67 and having a plurality of stop projections 68 spaced apart. In this 25 instance, this chain is operated by a step by step movement, first, to present one of the stop projections 68 to an adjustable abutment 69 on the lever 22 and next to present a space between two stop projections 68 to 30 said abutment 69. If the abutment 69 meets the space, then the lever 22 can make a full movement consequently operating the pawls 15 and 16 and moving the transporting carrier 10 to a distance to present another tube 35 frame and its spool to the wiping-in mechanism. If, however, a projection 68 is presented to the abutment 69, then the movement of the lever 22 is limited or not completed, with the result that the pawls 15 and 40 16 ride on the ratchet wheel 14 without operating the transporting carrier 10, so that the wiping-in mechanism moves from the transporting chain to wiping-in position back to the carrier 10 and then takes the same tube 45 frame which it had operated immediately prior thereto and repeats the wiping-in operation. While, in this instance, the limiting device limits the movement of the lever 22 every other time, it is apparent that the 50 invention is not limited to this arrangement since the size or number of limiting stops may serve to suspend the feed of the transporting carrier for any desired number of wiping-in repeats by the same tube frame. 55 For moving the limiting or selecting mechanism, a ratchet wheel 70 may be arranged on the shaft of the sprocket wheel 67 and with this ratchet wheel, a pawl 71 may engage, this pawl being pivoted at 72 to an arm 73 which swings on the shaft 23 on which the 60 two arm lever 22 also turns. A spring 75 connects this pawl 71 with the arm 73 to hold the pawl 71 normally in contact with the ratchet wheel 70. An arm 76 rigidly secured 65 to the arm 73 has a link 77 pivotally con-

ected thereto and extending downwardly therefrom to a bell crank lever 78, Fig. 1, pivoted at 79 to the loom frame 1 and having a roller 80 at its other end cooperating with a cam member 81 adjustably secured to a wheel 82 mounted on the drive shaft 2. With the rotation of the drive shaft 2, the bell crank 78 is periodically engaged by the cam 81 and raises and lowers the link 77. 70 With the raising of the link the pawl 71 rides upwardly on the ratchet wheel 70 without operating the latter, but with the lowering of the link, the pawl 71 advances the ratchet wheel 70 one step thus moving the endless selecting or eliminating device one step. A stop pawl 83 pivoted at 84 cooperates with the ratchet wheel 70 and holds the latter in the position to which it is moved. To render this limiting mechanism inoperative at will, a rod 71^a is connected 75 to the upper end of the pawl 71 and has a hand piece 71^b which is adapted to interlock with the hook 71^c to hold the pawl or detent 71 so it will not engage the ratchet wheel of the limiting mechanism. 80 When the shearing mechanism cuts the pile, it produces a lot of short pieces of yarn which cling to the yarn projecting from the tube frames. In previous machines these 85 small pieces on the projecting ends of the yarn on the tube frames have not been objectionable because the tube frames have been moved to the transporting chain and are immediately carried by the latter. As the transporting chain is of considerable length these short pieces drop off before a tube frame again wipes-in the yarn carried by it. In this machine, however, where each tube frame is successively employed for wiping-in two or more pattern lines, these short pieces do 90 not have opportunity to detach themselves from the depending portions of the yarn on the tube frames and as a consequence will be wiped-in the fabric on each successive operation of the tube frame unless some means is provided to prevent such action. In order to prevent this action, means is provided for wiping or removing these short pieces of yarn or fibre from the depending ends of yarn on each tube frame after each wiping-in operation of a tube frame. In this instance, this wiping means is in the form of a comb 85 secured to the knife carrier 42 and extending longitudinally of said carrier above the knife 95 blade 43, the comb having longitudinally extending slots 87 through which screws 86 pass in order that the comb 85 may be adjustable longitudinally of the row of yarn strands to properly position the comb with reference to the strands. The wipe-off comb being carried by the knife carrier 42 and the comb being directly beneath the tube frame as the latter moves upwardly, the yarn strands projecting from the tube frame are drawn upwardly through the slots of the comb or 100

105

110

115

120

125

130

wiper and all short pieces are removed from such strands so that, when the tube frame repeats its wiping-in action, the short pieces of yarn are not woven in the completed fabric.

In order that a patterned pile fabric of fine quality and close texture may be produced without pattern distortion, the present invention provides means for modifying the take-up during repeats of wiping-in action by the same tube frame with the result that successive repeats of the pattern line by any tube frame may be closely beaten up and consequently occupy substantially the same space longitudinally of the fabric that is ordinarily occupied by a single pattern line.

The modification of the take-up action may be variously contrived, the essentials in this respect being that such change in the take-up 20 be so coordinated with the repeated wiping-in action of the same tube frame that the two or more repeats of the same pattern line may be beaten up to occupy a close relation longitudinally of the fabric.

25 In the present embodiment of this feature of the invention the take-up is controlled in its action by or through the carrier chain operating mechanism, such that when the same tube frame is to wipe-in two or more 30 pattern lines in succession, the take-up shall be modified to cause the plural number of the same pattern lines to be beaten up into closer relation than is ordinarily the case.

35 Mounted at the front of the loom frame is the take up or spike roll 103 which is mounted for rotative movement in bearings 104. Secured to the take-up or spike roll 103 is a worm wheel 105 which engages with a worm 106 on a shaft 107, which is supported 40 for rotative movement in bearings 108, Fig. 9.

Secured to the shaft 107 is the toothed member or disk 109, which is engaged by a pawl 110 carried by a sleeve 111 loosely mounted on the shaft 107.

45 Connected to the sleeve 111 is the rod 112 having its rear end connected at 113 with the two arm lever 114 pivotally mounted on the loom frame at 115. The lower arm 116 of the lever 114 carries a roll 117 which is 50 adapted to be engaged by the cam projections 118 mounted on the cam disk 119, the construction being such that during normal operations of the loom without repeats of the wiping-in action by a tube frame the lever 55 114 will be moved to cause the pawl 110 to turn the worm shaft 107 and perforce to turn the take-up or spike roll 103. The spring 120 normally acts to move the roll 117 into engagement with the cam projections.

60 Connected to the two arm lever 22 at 121 is a take-up controller 122 herein shown as a rod extending downwardly from the lever 22 and pivotally connected at its lower end at 123 with a bell crank lever 124 pivotally 65 mounted at 125 to a cross girth 126. One

arm of the bell crank lever 124 is connected at 127 to a take-up controlling rod 128 mounted for sliding movement in the bearings 129 and carrying at its end remote from the bell crank lever a projection 130.

Rising from the cross girth 126 is a bracket member 131 into which is threaded an adjustable stop 132 which is shown in the present instance as an adjusting screw, the end of which at 133 extends towards the lever 114.

During normal weaving operations when each tube frame is caused to wipe-in a single row of tufts the two arm lever 22 will partake of its full feeding movement to actuate the transporting carrier 10 and at such times the projection 130 on the rod 138 is withdrawn from between the end of the adjusting screw and the arm of the bell crank lever 114, with the result that the cloth take-up will act to take up the cloth after each wiping-in action.

When, however, the selecting or limiting mechanism presents one of the upstanding stops 68 to the end of the pin 69, the two arm lever 22 will be arrested in its movement and the take-up controller rod 122 will be held in a raised or intermediate position, with the result that the bell crank lever 124, Fig. 10, will cause the projection 130 to be interposed between the limiting stop 122 and the upper arm of the two arm lever 114, so that the roller 117 will not have its full movement towards the cam projections 118 and consequently will be moved a less amount to take-up the cloth.

The construction is such that when each tube frame wipes-in only a single row of tufts the take-up will have a normal take-up movement, but when a tube frame is to wipe-in two or more successive rows of pattern forming tufts, the take-up will be modified or slowed down and it may be in some instances that it will be stopped altogether during the successive wiping-in actions by the same tube frame.

The operation of the invention will be understood from the foregoing but it may be summarized as follows: The tube frames 13 with the spools thereon are detachably secured in a known manner to the transporting carrier 10 and are successively brought to the wiping-in mechanism by the carrier through a step by step mechanism operated by the drive shaft 2 and having the pawls 15 and 16 which operate to turn the shaft 9 through the ratchet wheel 14. The wiping-in mechanism removes each tube frame presented to it with the spool thereon from the transporting chain and presents the yarn to the fabric being woven. After the tufts are formed, the shearing mechanism severs the yarn and immediately thereafter the wiping-in mechanism returns the tube frame and the spool to the transporting carrier. As the shearing blade 43 approaches the yarn, the comb or wiper 85 straddles the different strands of yarn projecting from the tube frame so that, as the tube frame moves away from the

70

75

80

95

100

105

110

115

120

125

130

shearing mechanism, the yarn strands are wiped to free them from the short fibres. In this illustrated construction, the feeding mechanism is rendered inoperative on the 5 transporting chain 10 on every other operation of the wiping mechanism, this being effected through the limiting stops 68 passing into the path of the abutments 69 on the lever 22, on alternate downward movements 10 of said lever so that the pawls 15 and 16 do not turn the ratchet 14. The limiting stops 68 have a step by step movement effected through the pawls 71 which are controlled from the driving shaft 2. The carriers for 15 the shearing or cutting blades 43 and 45 are supported intermediate their ends by means which does not interfere with their movements toward and from each other.

When the selecting or limiting mechanism 20 calls for repeats of wiping-in action by any one of the tube frames the cloth take-up action is modified or suspended so that the two or more rows of patterned tufts successively introduced by any tube frame will be beaten 25 up close in the fabric and occupy space longitudinally of the fabric substantially equal to the space ordinarily occupied by a single row of tufts.

The foregoing mechanism is particularly 30 designed for weaving patterned Axminster fabrics of high quality or close weave without pattern distortion. Heretofore the substantial maximum of pattern lines possible in a patterned Axminster fabric has been ten 35 due to the fact that if more pattern lines were employed, a flattening of the pattern would occur. This is overcome by repeating the pattern lines one or more times and beating the pattern lines to a higher degree in 40 order to increase the number of lines per inch to obtain a pattern without distortion. The present application does not show a beating mechanism but the loom is equipped with the usual beating mechanism now well known, 45 the increased beating being obtained by slowing down or modifying the action of the take-up mechanism so that the beating action on the wiped-in pattern lines is increased and no pattern distortion results.

50 What is claimed is:—

1. In an Axminster loom, the combination with a transporting carrier of a plurality of tube frames thereon, a wiping-in mechanism to which the tube frames are carried successively by the transporting carrier, a pawl and ratchet mechanism for shifting the carrier step by step, and mechanism for actuating said pawl and ratchet mechanism, of means for limiting the movement of the last 55 named mechanism periodically to prevent the pawl and ratchet mechanism moving the transporting carrier, said means comprising an abutment on the pawl shifting mechanism and an endless limiting device having projections and spaces between the projections,

the projections cooperating with the abutment on the pawl shifting mechanism to limit the movement of the latter, and spaces permitting the abutment to pass between the projections in order that a full movement of 70 the pawl shifting mechanism may take place.

2. In an Axminster loom, the combination with a transporting carrier, a tube frame carried thereby, a wiping-in mechanism for moving the tube frame toward and from the 75 transporting carrier, and a shearing mechanism for shearing the wiped-in yarn from the yarn on a tube frame of a wiping means carried by the shearing mechanism and engaging with the strands on the tube frame 80 to remove the short yarn therefrom as the tube frame is moved away from the shearing mechanism.

3. In an Axminster loom the combination with a transporting carrier, tube frames carried thereby, a wiping-in mechanism for moving the tube frames toward and from the transporting carrier, and a shearing mechanism embodying two knife carriers each of which support a cutting knife, a comb wiper 85 carried by one of the knife carriers above the knife thereof and engaging with the projecting ends of the strands on the tube frame as the latter moves away from the knife carriers.

4. In an Axminster loom, the combination with a transporting carrier, a plurality of tube frames thereon, a wiping-in mechanism to which the tube frames are carried successively by the transporting carrier, a ratchet 100 wheel connected with the carrier for imparting a movement to the carrier through the length of the latter, a pivotally mounted lever, a pawl carried by the lever for operating the transporting carrier, an abutment 105 mounted on the lever, mechanism for controlling the lever movements comprising a member operated continuously during the loom operation and provided with spaced stops which cooperate with the abutment to limit the lever movement and prevent travel of the transporting carrier periodically.

5. In an Axminster loom, the combination with a transporting carrier, tube frames carried thereby, and wiping-in mechanism for 115 moving the tube frames toward and from the transporting carrier, of a wiper engaging with the strands on the tube frame to remove the loose fibres from the yarn as the tube frame moves away from the work after a 120 wiping-in operation of the wiping-in mechanism.

6. In an Axminster loom, the combination with a transporting carrier, a tube frame carried thereby, and wiping-in mechanism for moving the tube frame toward and from the transporting carrier, of a comb for engaging with the strands on the tube frame, and means for operating said comb to cause it to engage said strands to remove the loose fibres 130

- from the strands while the tube frame is being carried away from the work by the wiping-in mechanism after a wiping-in operation.
7. In an Axminster loom, the combination of a cloth take-up, a transporting carrier, a plurality of tube frames mounted thereon, a wiping-in mechanism, means for feeding the transporting carrier to present a tube frame to the wiping-in mechanism, means actuated by a going part of the loom for suspending the feeding movement of the transporting carrier at predetermined intervals that the wiping-in mechanism may wipe-in yarns from the same tube frame a plurality of times, and means for modifying the action of the cloth take-up during successive wiping-in operations by the same tube frame.
8. In an Axminster loom, the combination of means for taking up the cloth as it is woven, a transporting carrier, a plurality of tube frames mounted thereon, a wiping-in mechanism, means for feeding the transporting carrier step by step throughout its length to present a tube frame to the wiping-in mechanism, means actuated by a going part of the loom for suspending the feeding movement of the transporting carrier at predetermined intervals that the wiping-in mechanism may wipe-in yarns from the same tube frame a plurality of times, and means for modifying the cloth take-up during successive wiping-in operations by the same tube frame that the plurality of pattern lines may occupy substantially the same space ordinarily occupied by a single pattern line.
9. In an Axminster loom, the combination of cloth take-up mechanism for taking up the cloth as it is woven, a transporting carrier having tube frames thereon, a wiping-in mechanism, an actuator for moving the transporting carrier to present a tube frame to the wiping-in mechanism, means for suspending the effective operation of the actuator at intervals that the wiping-in mechanism may wipe-in successive rows of pile forming tufts from the same tube frame; and means for modifying the effective operation of the cloth take-up mechanism during successive wiping-in operations by the same tube frame that the plurality of pattern lines formed by the same tube frame may be beaten up into close relation to form a quality pile fabric.
10. In an Axminster loom, the combination of a transporting chain carrying a series of tube frames, a wiping-in mechanism, actuating means for the transporting chain to present a tube frame to the wiping-in mechanism, means for suspending the effective operation of the actuating means for the transporting chain at intervals that the same tube frame may wipe-in successive rows of pile forming tufts, a cloth take-up mechanism and operating means therefor to take-up the cloth as it is woven, and a take-up controller op-

erated from the actuating means for the transporting chain for modifying the action of the take-up mechanism during successive wiping-in operations of the same tube frame.

11. In a loom for weaving pile fabrics, the combination of means for forming two or more rows of the same pattern lines in succession, a cloth take-up mechanism and means for operating the same to take-up the cloth, controlling means for the take-up mechanism for modifying the take-up action of the take-up mechanism during the formation of two or more rows of the same pattern lines in succession so that the said pattern lines may be beaten up into close relation to form a quality fabric without distortion of the pattern.

12. In a loom for weaving pile fabrics, the combination of means for forming two or more rows of the same pattern lines in succession, a cloth take-up mechanism and means for operating the same to take-up the cloth, controlling means for the take-up mechanism for slowing down the take-up action of the take-up mechanism during the formation of the two or more rows of the same pattern lines in succession that such plurality of successive pattern lines may occupy substantially the same space longitudinally of the fabric that is ordinarily occupied by a single row.

13. In an Axminster loom, the combination of a transporting carrier having a series of tube frames, a wiping-in mechanism, actuating means for the carrier for presenting tube frames to the wiping-in mechanism, selecting or limiting mechanism for determining the effective operation of the actuating means, a take-up mechanism for taking up the cloth as it is woven, take-up controlling means operated from the selecting or limiting mechanism for slowing down the take-up when the selecting or limiting mechanism indicates a suspension of movement of the transporting carrier that the same tube frame may wipe-in a plurality of times.

In testimony whereof, I have signed my name to this specification.

JOSEPH A. COYLE.
